LATTICE PANEL SPACER FOR HOLDING A
PLURALITY OF LUGS IN A COMPACT,
RIGID UNIT

Francis C. Huebner, Fresno, Calif.

Application March 27, 1950, Serial No. 152,048

7 Claims. (Cl. 105—369)

1

My invention relates to a lattice panel spacer for holding a plurality of rows of stacked lugs or boxes, known collectively as a pack, in a rigid unit by frictional contact between the spacers and the lugs forming the pack. It is known that in existing art there is a gate, or spacer having horizontal binder elements attached to upright posts which is used in a limited manner for the purpose of making packs of lugs rigid. In the present art however, it is necessary to space the stacks of lugs apart in the rows of stacks of lugs to make room for inserting the posts and when it is desired to limit the size of the space, or to place the stacks of lugs in contact relation, and there is insufficient space for the disposal of the posts, the art as heretofore developed cannot be used. In my improvement it is optional whether space is left between adjacent stacks within the row of stacks, or whether the size of the space is diminished, or whether the stacks are positioned in contact relation.

Another object is the formation of a pack for shipping which is held rigidly both horizontally and vertically.

Another object is that the relative cost of the lattice panel spacers is less than the devices now used for that purpose.

These and other objects hereinafter referred to are accomplished by the lattice panel spacers hereinafter described and illustrated in the accompanying drawing, in which:

Fig. 1 is a fractional view of a railroad car loaded with boxes or lugs with a space in the approximate lineal center of the car adapted to receive means for compressing the pack at either end of the car in a rigid unit.

Fig. 2 is a cross sectional view of the loaded car shown in Fig. 1 along broken line 2—2.

Fig. 3 is a cross section view of a loaded car showing ventilating avenues between rows of stacks and showing my lattice panel spacer applied for frictional contact with the lugs, and the relative location of the cross metal holding strips across the face of the lugs.

Fig. 4 is a cross section view of the car shown in Fig. 1 along broken line 4—4 showing a heavy end gate used at an end of the rows of stacks forming a pack.

Fig. 5 is a perspective view of a lattice panel spacer and a phantom view of a stack of boxes showing a hook formed at the upper end of the metal support, and adapted to engage the upper box in a stack of boxes.

Fig. 6 is an enlarged sectional view of a fractional wooden strip shown in Fig. 2 approximate-

2

ly on line 6—6, showing the metal strip countersunk within the wooden strip.

Fig. 7 is a similar view to Fig. 5 showing a modified form of elements in which a wire is substituted for a flat metal strip in the lattice panel spacer and the means for holding it thereon is an ordinary double pointed staple.

Referring to the drawing, in Fig. 1 I have shown a fractional railway car 10 in which a plurality of lugs 11 of uniform rectangular shape are placed in stacks 40, and stacks 40 are placed in rows crosswise in the car. The loading of the car is continued by adding additional rows of stacks 40 to the first row placed along an end of the car, with spacers 13 hereinafter described inserted between said rows of stacks 40 until the packs, or half loads, from either end approach the center of the car where a small space is left for the insertion of heavy gates 20 hereinafter described and screw expanding units 22 which can be used to clamp the two packs toward the end of the car in which the pack is located.

It is noted that between adjacent rows of stacks 40 when placed crosswise within the car are spacers 13. As shown in Figs. 2 and 3 spacer 13 consists of a lattice panel. Said lattice panel is constructed of a plurality of wooden strips 14 spaced apart the length of the height of a unit lug 11. The wooden strips 14 are held in such parallel, spaced relation with metal strips 15 which are attached thereto with nails 23, shown in Fig. 6, or staple 24 shown in Fig. 7. Other well known means for attaching the metal strips to the wooden strips can be substituted. Metal strips 15 should be countersunk in wooden strips 14 so that when a lattice panel is assembled between rows of lugs, and juncture 29 (see Fig. 6) of wooden strip 14 with metal strip 15 is between the sides of adjacent lugs, the metal strip 15 will not interfere with free frictional contact of wooden strip 14 with the contacting faces of lugs 11 on either side thereof.

It is noted that metal strip 15 can be a round or angular wire if desired. The strip or wire is very thin and if it is not deeply countersunk when the lattice panel is constructed, when pressure is applied to the pack of lugs and lattice spacers 13, the wires or metal strips which are projecting will be countersunk in the sides of the lugs so that frictional contact of the wooden strips with adjacent lugs will not be impaired.

When lattice panels 13 are assembled with the rows of stacks 40, the preferred practice is to have the wooden strips 14 horizontally disposed so that one of said wooden strips 14 extends along

lugs 11 aligned in a horizontal row of stacks 40. But, the lattice panel spacers 13 can be applied so that the wooden strips 14 are positioned upright along the approximate center of each stack 40 and in that case the metal straps 15 would extend horizontally across the pack.

Continuing on the preferred practice of applying my invention, it is essential that the wooden strips 14 be approximately horizontally aligned with the sides of lugs 11 which are horizontally aligned in the row of stacks 40. That relation is positive when compression is applied to the assembled pack of lugs 11 and spacers 13. Prior to that status and in the formation of the load, special means must be taken to hold spacers 13 in the position into which they are finally clamped. To accomplish this I have formed the upper end of the wire or metal strip 15 into angular hooks 16 as shown in Fig. 5, which hooks are adapted to engage the top tier of lugs 11 aligned with the wooden strip. In Fig. 3 I have shown another method for temporarily holding spacer 13 in the position desired by nailing the topmost wooden strip 14 in the spacer 13, with nails 18, to the top tier of lugs 11 in the row of stacks 40. From that position the lattice panel can drape downward over the row of stacks 40.

When loading a car with lugs, alternate rows of stacks 40 and lattice panel spacers 13 should be continued from each end of the car until the two packs, or half loads reach a selected short distance from the center cross line of the car as shown in Fig. 1. Then a heavy gate 20 is placed crosswise within the car at the end of each pack. Gate 20 consists of upright supports 19 and cross members 21 rigidly attached thereto. Upright supports 19 should be positioned at right angles to cross members 21, and be spaced apart so there is one support 19 for each stack of lugs 40, and aligned therewith. When a gate 20 is positioned at an end of each pack as shown in Fig. 1, means for compressing the two packs in two units, and each against the end of the car in which the pack is located consists of a pair of screw jacks 22 which can simultaneously provide screw pressure for each of the two packs forming the load, the direction of such pressure being toward the ends of the car. These jacks 22 can be left within the car while the lugs are being transported, or after compression blocks can be inserted between the two packs to hold such compression and the jacks 22 removed for further use.

An analysis of the invention shows that by the use of the lattice panel spacers the horizontal strips when frictionally clamped against the sides of the lugs, said lugs are firmly held against horizontal shocks and disturbances, and the metal strips being attached to the horizontal strips, hold the packs vertically rigid so that unusual movements of the car cannot disarrange the top tiers of the packs.

While I have described my means for loading lugs in cars, the same means can be applied to load boxes of uniform rectangular shapes.

In the foregoing specification I have described the horizontal wooden slats as a necessary element in my invention. But it is here noted that within the scope of my invention horizontal metal straps can be substituted for the wooden ones by having the substituted straps faced to form a frictional surface so they will adhere to the lugs under pressure. Or, other suitable material can be thus used.

Having described my invention I claim as new and ask for Letters Patent.

1. A load of lugs held rigidly in bulk in a car having a floor, sides and ends, said load comprising a plurality of stacks of lugs aligned in rows parallel to an end of the car and in parallel relation to each other, spacers between contiguous rows forming said load and in frictional contact with the lugs of each row, each spacer being constructed of a plurality of horizontal binder strips having opposed vertical faces and holding strips attached thereto at approximately right angles, said holding strips extending entirely between opposed vertical faces of said binder strips, the said binder strips being vertically spaced apart from each other a distance substantially equal to the height of a lug.

2. A load of lugs as defined in claim 1 including means carried by said spacers, engaging the top lug of an adjacent row and arranged to position said spacers so that said horizontal binder strips engage each of said lugs between the top and bottom thereof.

3. Spacer means for holding a plurality of stacks of lugs in parallel rows, said spacer comprising a plurality of spaced parallel strips of uniform thickness, the spacing between said strips being substantially equal to the height of one of said lugs, means holding said strips in spaced relation with opposed faces thereof lying in parallel planes, said holding means lying entirely between said planes.

4. Spacer means as defined in claim 3 wherein said strips are elongated strips of wood having transverse depressions across one face and wherein said holding means are elongated strips of metal extending across and fastened to all said strips of wood and lying in said depressions.

5. Spacer means as defined in claim 3 including hook means fixed to said spacer and arranged to engage the top lugs of a row and adapted to suspend said spacer with said strips extending along edge faces of the lugs of said row.

6. Spacer means as defined in claim 3 wherein said strips are elongated strips of wood having transverse grooves in one face and wherein said holding means are elongated strips of metal extending across and fastened to all said strips of wood and lying in said grooves, said strips of metal being transversely bent at one end to define hook means adapted to suspend said spacer from the top lugs of a row with said strips extending horizontally along edge faces of the lugs of said row.

7. Spacer means as defined in claim 3 wherein said strips are elongated relatively stiff strips of material and wherein said holding means are elongated flexible strips of metal.

FRANCIS C. HUEBNER.
